UNITED STATES PATENT OFFICE.

CHARLES ESPLIN, OF MINNEAPOLIS, MINNESOTA.

CIRCULAR-SAW MILL.

SPECIFICATION forming part of Letters Patent No. 295,991, dated April 1, 1884.

Application filed December 10, 1883. (No model.)

To all whom it may concern:

Be it known that I, CHARLES ESPLIN, a subject of the Queen of Great Britain and Ireland, and a resident of Minneapolis, in the 5 county of Hennepin, in the State of Minnesota, have invented certain new and useful Improvements in Circular-Saw Mills, of which the following specification is a full, clear, and exact description, reference being also had to the accompanying drawings, in which—

Figure 1 is a side elevation. Fig. 2 is a front view of a portion of the front of the upper saw-frame and swinging yoke-frame. Figs. 15 3, 4, and 5 are detached perspective views of the rear end of the swinging yoke-frame and its supporting-bracket and the upper saw-mandrel journal. Fig. 6 is a plan and partial horizontal section of the machine. Fig. 7 is a 20 plan view of the swinging yoke-frame detached.

A' is the "husk" or bed frame, having mounted thereon the lower saw-mandrel, B', lower saw, B², main driving-pulley B³, lumber-supporting rollers C' C² C³, and spreader 25 or wedge-plate D. The husk-frame is supported loosely at its rear corners by bed-plates a' a², the latter bolted or otherwise rigidly attached to the timbers or floor of the mill. The upper saw-supporting frame, consisting 30 of side frames E' E², and cross-brace frame E³, is attached rigidly to the husk-frame A', upon one side only of the saw-mandrel B', the object to be hereinafter explained. By this arrangement the whole husk-frame and its attached parts may be adjusted bodily upon the 35 plates a' a², so that after the different parts are once adjusted with reference to each other no danger exists of disarrangement by the separate adjustment of each distinct part.

40 Heretofore in machines of this kind the husk-frame was stationary, and the saw-mandrel B' and other parts had each its own separate means of adjustment with relation to the husk-frame, and in adjusting one part it was necessary to also adjust all the other parts to 45 correspond, which was a very laborious, uncertain, and delicate process, as a very slight change produced marked results in the action of the saws, and also rendered the heating of the arbor, &c., a very frequent occurrence. 50 By my arrangement, however, after the parts

are once adjusted upon the husk-frame, no danger exists of disarrangement, as all the parts move together with the frame. It also enables the husk-frame and its attached parts to 55 be moved bodily nearer to or farther away from the line of travel of the saw-carriage, either both ends alike or one end at a time.

Any suitable means may be used to move the husk-frame A' upon the plates a' a², either 60 levers, racks and pinions, wedges, or screws, &c.; but I prefer to use large screws F' F², each journaled at one end in lugs a⁵ a⁶ upon the plates a' a², and tapped through nuts a⁷ a⁸, lying loose in sockets a⁹ a¹⁰ upon the husk-frame A', as they not only operate easily and quickly, but firmly hold the frame A' wherever placed. The nuts a⁷ a⁸, as will be seen in Fig. 6, are formed with curved faces, so 65 that they will roll in the sockets a⁹ a¹⁰ if the frame A' is adjusted more at one end than the other, (which is sometimes necessary,) and thereby prevent cramping. Large bolts fitting through slots or enlarged holes in the husk-frame will also be used to clamp the frame 70 to the bed-timbers after adjustment by the screws F' F², so as not to depend solely upon the latter to hold the frame.

I do not wish to confine myself to any particular method of moving the husk-frame, as 80 any well-known suitable mechanical device may be used.

The plates a' a² may be connected together by tie-rods, or one single frame or plate larger than the husk-frame may be used in place of 85 the separate plates a' a².

As before stated, the frame E' E² E³, for supporting the saw, is attached to the husk-frame upon one side only of the mandrel B' of the lower saw, instead of upon both sides, as heretofore. This is a very important feature of 90 my invention, as it renders the saw-mandrel and main driving-pulleys easily accessible for removal or repairs, while in machines of this kind, where the upper saw-supporting frame 95 is arranged upon both sides of the lower saw-mandrel, to remove the mandrel it is necessary to either first remove the upper frame or the main driving-pulley and the saw before the mandrel can be removed; but by the arrangement shown no obstruction exists above the 100 saw-mandrel. This arrangement also greatly

facilitates the oiling and cleaning of the mandrel and the filing of the saw. It also greatly facilitates the operation of the tightener G' and the placing of the upper saw-driving belt, 5 G^2 , upon the pulleys $G^3 G^4 G^5 G^6$, and leaves the view of the operator unobstructed, so that he can see the saws at all times. The mandrel H' of the upper saw, H^2 , is journaled by its ends in a yoke-frame, H^3 , attached across the 10 faces of the side frames, $E' E^2$, and adapted to be adjusted higher and lower by the screws $K' K^2$ and gears and pinions K^3 , as shown.

H^4 is an arm attached to or forming part of the yoke-frame H^3 , and carrying the saw-guide H^5 . The face of the side E' for about one-half its length down from the top is made concave, as shown at e' , Fig. 6, and the face of the yoke H^3 where it comes in contact with this concave surface is formed correspondingly 20 convex, as shown at e^2 , the line of the center of the curve of these convex or concave surfaces running down through the center of the mandrel in one direction and through the center of the side E' in the other direction, as indicated by dotted lines at x in Fig. 7. The rear end of the mandrel H' is supported by a journal-box, H^6 , the latter resting upon the flat end H^7 of the yoke-frame. This flat end in turn rests upon a bracket, H^8 , adapted to 30 be moved up and down along the face of the side frame, E^2 , by the screw K^2 , as before described. The bracket H^8 , and also the convex end e^2 of the yoke-frame H^3 , are bolted to the side frames, $E' E^2$, by bolts $g' g^2$, fitting through 35 slots $y' y^2$ in the side frames, so that the yoke-frame may be firmly attached to the side frames, while at the same time, by means of the slots, it is left free to be adjusted higher and lower by the screws $K' K^2$. By loosening or tightening one of the set-screws which hold the pinions K^3 to their shaft the screws $K' K^2$ may be operated together or separately to adjust 40 one or both ends of the mandrel H' .

m' is a screw journaled in a lug, m^2 , upon the 45 outer corner of the bracket H^8 , and tapped through a lug, m^3 , upon the outer end of the flat part H^7 of the yoke-frame H^3 , by which means the rear end of the yoke-frame may be adjusted nearer to or farther away from the 50 side E^2 , and thereby swing the yoke-frame upon the convex and concave surfaces $e' e^2$ as a center, and adjust or "line" the upper saw, H^2 , to any required extent, the curved surfaces $e' e^2$ permitting this swinging movement without 55 danger of cramping or straining the parts.

m^4 is another screw, similar to the screw m' , journaled in a lug, m^5 , on the end H^7 of the yoke-frame H^3 , and tapped into the lower section of the journal-box H^6 , by which means 60 the journal-box may be adjusted along the end H^7 in a line parallel with the mandrel H' , and carrying the mandrel with it. This mandrel H' is provided with a shoulder at n' in front of, and a collar, n^2 , Fig. 6, in the rear of, the 65 journal-box, so that the mandrel will be moved endwise with the journal-box when the latter is adjusted by the screw m^4 . By this simple

arrangement the upper mandrel, H' , may be easily and quickly adjusted in all directions by merely turning the two screws m' and m^4 . 70 Bolts $r' r^2$ will be arranged to clamp the journal-box H^6 to end H^7 , and to also clamp the latter to the bracket H^8 after the mandrel and saw is adjusted, so as not to depend wholly upon the screws $m' m^4$ to hold the parts in place. 75

Having described my invention and set forth its merits, what I claim is—

1. In a circular-saw mill, the combination of the laterally-adjustable husk-frame A' , supporting the saw or saws $B^2 H^2$, stationary 80 bed-plates $a' a'$, on which the said husk-frame is supported, and by which it is held in position, and means for laterally adjusting the said frame upon the said bed-plates, substantially as and for the purpose herein specified. 85

2. The combination of the laterally-adjustable husk-frame A' , having the mandrel B' , saw B^2 , lumber-supporting rollers $C' C^2 C^3$, and wedge-plate D , mounted thereon, stationary bed-plates $a' a'$, on which the said husk-frame is supported and by which it is held in position, and means for laterally adjusting the said frame upon the said bed-plates, substantially as and for the purpose herein specified. 90

3. The combination of the laterally-movable 95 husk-frame A' , having the mandrel B' , saw B^2 , lumber-supporting rollers $C' C^2 C^3$, wedge-plate D , and upper saw-supporting frame, $E' E^2 E^3$, mounted thereon, stationary bed-plates $a' a'$, on which the said husk-frame is supported and 100 by which it is held in position, adjusting-screws $F' F^2$, nuts $a^1 a^2$, and sockets $a^9 a^{10}$, substantially as and for the purpose herein specified.

4. In a circular-saw mill, the combination 105 of the husk-frame A' , carrying the lower saw, B^2 , the upper saw-supporting frame, $E' E^2 E^3$, mounted on the husk-frame, fixed bed-plates $a' a^2$, and frame-adjusting screws $F' F^2$, substantially as herein specified.

5. In a circular-saw mill, the combination 110 of the husk-frame A' , carrying the mandrel B' , saw B^2 , and driving-pulley B^3 , and the upper saw-supporting frame, $E' E^2 E^3$, attached to the said husk-frame, located entirely at one side of the said mandrel B' , substantially as and for 115 the purpose herein specified.

6. In a circular-saw mill, the combination 120 of the husk-frame A' , carrying the lower mandrel, B' , saw B^2 , and saw-driving pulley B^3 , the upper saw-supporting frame, $E' E^2 E^3$, the yoke-frame H^3 , carrying the upper saw-mandrel, H' , and adapted to swing laterally and vertically around the center of one mandrel-bearing, and means, substantially as described, for adjusting it at the other mandrel-bearing both horizontally and vertically, for the purpose herein 125 specified.

7. In a circular-saw mill, the husk-frame A' , carrying the lower saw, upper saw-frame having concave face e' , yoke-frame H^3 , carrying 130 the upper saw-mandrel and saw, and having convex face e^2 , and means for adjusting said yoke-frame, substantially as shown.

8. The combination of the frame $E' E^2 E^3$,

having concave face e' , yoke-frame H^3 , carrying the upper saw-mandrel, H' , and having convex face e^2 , journal-box H^6 , bracket H^8 , and means for adjusting said yoke and mandrel, substantially as specified.

9. The combination of the frame $E' E^2 E^3$, having the concave face e' , yoke-frame H^3 , having convex face e^2 , guide-arm H^4 , guide H^5 , mandrel H' , saw H^2 , journal-box H^6 , bracket H^8 , and means for adjusting said yoke-frame, substantially as described.

10. The combination of the frame $E' E^2 E^3$,

having the concave face e' , yoke-frame H^3 , having convex face e^2 , and carrying the mandrel H' and saw H^2 , journal-box H^6 , bracket H^8 , and screws $K' K^2$, substantially as and for the purpose specified.

In testimony whereof I have hereunto set my hand in presence of two subscribing witnesses.

CHARLES ESPLIN.
